Mr. President:

UNITED STATES PATENT OFFICE.

GEORGE A. L. DRAWS, OF MILWAUKEE, WISCONSIN.

VENTILATOR.

1,254,216.

Specification of Letters Patent. Patented Jan. 22, 1918.

Application filed January 13, 1917. Serial No. 142,164.

To all whom it may concern:

Be it known that I, GEORGE A. L. DRAWS, a citizen of the United States, and resident of Milwaukee, in the county of Milwaukee and State of Wisconsin, have invented certain new and useful Improvements in Ventilators; and I do hereby declare that the following is a full, clear, and exact description thereof.

10 My invention relates to new and useful improvements in ventilators, more particularly of that type adapted to be positioned in a window or other opening for preventing a direct draft therethrough.

15 It is in general the object of my invention to simplify the structure and improve the efficiency of devices of this character, and it is more particularly an object in this connection to provide a ventilator structure 20 which may be assembled and disassembled in a most ready manner.

25 A further object resides in the provision of a means whereby the inlet flow of air through the ventilator may be readily controlled.

30 A still further important object resides in the provision of a ventilator of this nature including an open end passage way extending transversely of the window opening or other ventilating aperture and so arranged as to prevent a direct passage of air therethrough whereby lateral currents of air upon entering said passage way will be deflected to insure a flow of air through the 35 body of the ventilator.

35 A still further object resides in the provision of a valve controlled air outlet passage associated with the main inlet passage of the ventilator.

40 With the above and other objects and advantages in view, the invention resides more particularly in the novel combination, formation, and arrangement of parts herein-after described and pointed out in the appended claims.

45 In the drawings:

Figure 1 is a horizontal sectional view of a ventilator constructed in accordance with my invention, the plane of this view being indicated by the line 1—1 of Fig. 3.

Fig. 2 is a vertical longitudinal sectional view through the transverse head portion of the ventilator as indicated by the line 2—2 of Fig. 3.

55 Fig. 3 is a vertical sectional view through

the body of the ventilator on the line 3—3 of Fig. 1.

Fig. 4 is a detail sectional view of the shutter controlling means, on the line 4—4 of Fig. 5.

Fig. 5 is an elevational view of said shutter controlling means.

Referring now more particularly to the accompanying drawings, the present embodiment of my ventilator comprises a substantially T-shaped casing, the body of which is adapted to be positioned in a window or other ventilation opening, and which is open at the ends of its head portion and closed along the entire front of 70 said head portion whereby to prevent a direct draft through the window. The head portion of this casing is formed by an outer casting 5 including the front wall and top bottom and side wall sections which telescopically fit in corresponding wall sections of an inner casting 6, and are secured thereto, as by the screws 7. From points adjacent its ends, the front wall of the outer casting is bulged outwardly in a relatively 75 wide V and this wall is preferably provided with a pair of doors 8 whereby access may be had to the interior of the head portion. The inner casting 6 includes a rear wall 9 which fits against the wall of the building, 80 or other support and this wall is provided with an intermediately disposed aperture communicating with the body portion of the casing. At the sides of the aperture, the wall 9 is inwardly offset to form curved 85 deflecting surfaces 10 extending through substantially a quarter circle, and straight wall portions 11 extending at right angles to the body of the wall 9. Below the aperture of the wall 9, said wall is inclined rearwardly 90 from its bottom edge and terminates at the aperture in a horizontal portion 12. The body section of the ventilator comprises a main casting including the side walls 13, the main bottom wall 14 and a horizontal partition wall 15 disposed adjacent the main bottom wall 14 and defining therewith an air outlet passage. For securing this main casting to the inner casting 6 of the head section of the ventilator, the side walls 13 100 at their forward ends are inwardly offset to fit within the aperture of the rear wall 9 and are secured, as by the screws 16, to the portions 11 of the rear wall. The partition wall 15 is provided with upwardly 105

11

offset forwardly extending lugs 17 similarly secured to the horizontal portion 12 of the rear wall. The side walls 13 of the body section are preferably braced by vertical stiffening ribs 18 cast integrally therewith on their inner faces, and it is noted that the width of these ribs is such that they lie outwardly of the side edges of the aperture of the rear wall of the head portion whereby said ribs do not interfere with the free flow of air through the body of the ventilator. Incidentally it may be noted that the horizontal portion 12 of the rear wall is braced by rib members 19 formed integrally with said horizontal portion and with the inclined lower portion of the wall. The body section of the ventilator is completed by a top wall casting 20 secured to the upper edge portions of the side walls 13.

20 The entire ventilator casing thus described may be very readily assembled and disassembled, for its operative association with a window or other ventilator opening, whereby a free flow of air may be had through the ventilator opening without the inconveniences of a direct draft. It is noted that air may flow into the head section of the ventilator from either end thereof, and thence through the body section into the room. Should a relatively strong wind be blowing in a direction substantially parallel to the head section of the ventilator, passage of the wind therethrough without supplying a proper current of air to the body section of the ventilator is prevented by either of the deflector surfaces 10, which deflect the current of air into the bulged portion of the front wall of the head section and thus set up an eddy whereby a current will be supplied through the body section of the ventilator, it being noted that said deflector surfaces and said bulged portion of the front wall serve to define an offset of the passage way of the head casing section.

45 To properly cleanse the air as it passes through the ventilator, a sheet of screen material 21 is disposed at the juncture of the casing section and rests at its edges against the shoulders formed by the said offset of the side walls 13 and the securing lugs 16 of the partition 15, the upper edges of the screen resting against a depending bracing rib 22 of the top casting. This screen sheet is held in place by eccentrically pivoted plates 23 on the partition 15.

Taking up now the means for controlling flow of air through the ventilator, it is noted that the front and rear walls 9 of the head section casings are inwardly offset at their ends and secured to these inwardly offset end portions of the casing are the side bars 24 of a pair of rectangular frames which also include separable top bar sections 25 connected by bolts 26 passed through the laterally turned meeting ends thereof. Piv-

otally mounted in the inner portions of the side bars 24 which extend inwardly of the offsets of the walls are the pintles of series of shutter plates 27 and each of the shutter plates is provided at its inner edge with a laterally extending lug 28 which is pivoted to a common actuating bar 29 of the series of plates. Thus the shutter plates 27 are mounted in a most ready manner, and upon swinging their respective actuating bars 29 may be opened or closed to effectively control the passage of air through the ventilator, it being noted that the laterally turned ends of the transverse bar section of each end frame are extended in opposite directions whereby to permit a complete closing of the shutter plates. For actuating the shutter plates from the inner end of the body section of the casing, links 30 are pivoted to the upper portions of the shutter actuating bars 29 and to the ends of the cross arm 31 fixed on a shaft 32 which is journaled in the lower portion of the rear wall 9, and in a wall portion 33 integrally connecting the intermediate portions of the bottom 14 and partition 15, and incidentally strengthening said portions. Rotation of this shaft is controlled by a handle link 34 pivoted thereto, and to secure the shaft in any desired position, said link is provided with a lug 35 selectively engageable in one of a series of notches in a rack segment 36 secured to the wall portion 33.

Under certain severe conditions it may be possible for air to pass inwardly through the outlet passage of the ventilator, between the bottom 14 and partition 15, and to properly cleanse such possible inflow of air a pair of screen plates 37 are disposed in the outlet passage and are secured in place by eccentrically pivoted plates 39 pressing said screen plates against integral ribs projecting into the passage, the inner ends of the plates engaging in grooves 40 formed in the ends of inturned extensions 41 of the central journal wall 33. Under some conditions it may be desired to entirely close the outlet passage, and to accomplish this doors 42 are pivoted at the sides of the wall 33, these doors being normally held in raised positions by pawls 43 pivoted on the side walls 13.

From the foregoing description it will be seen that I have provided an efficient and exceedingly simple ventilator structure, which may be most readily assembled and disassembled.

What is claimed is:

1. A ventilator comprising a T-shaped casing including a body portion and a head portion, said head portion being formed by two telescoping sections, the outer section thereof being bulged outwardly in a relatively wide V and the inner section having its wall broken for communication with the

body portion, said wall being inwardly offset at the sides of its aperture to form curved deflecting surfaces, and means in the head portion for controlling the entrance of air thereto.

5 2. A ventilator comprising a T-shaped casing including a body portion and a head portion, the outer wall of said head portion being bulged outwardly in a relatively wide 10 V and the inner wall being apertured for communication with the body portion, inwardly offset curved portions extending along the sides of said aperture to provide a communication with the atmosphere and to 15 form air deflecting surfaces extending through substantially a quarter circle in said head portion, a passage beneath said aperture and communicating with the atmosphere and with a passage in the body 20 portion and the passage formed by said curved deflecting surfaces, and means in the head portion for controlling the entrance of air thereto.

3. A ventilator comprising a T-shaped casing including a body portion and a head 25 portion, said head portion being formed by two telescoping sections, the outer section being bulged outwardly in a relatively wide V and the inner section having its wall apertured to communicate with the body 30 portion, inwardly offset and curved deflecting surfaces in the wall of the inner section and at the sides of its aperture, said wall being inclined rearwardly from its bottom edge and terminating at the aperture and 35 forming openings communicating with the atmosphere, and a partition near the bottom of the body portion forming an outlet passage communicating with said openings formed in the bottom of the wall of said 40 inner section substantially as described.

In testimony that I claim the foregoing I have hereunto set my hand at Milwaukee, in the county of Milwaukee and State of Wisconsin.

GEORGE A. L. DRAWS.
